(57) **CLAIM**

The ornamental design for a food battering machine, as shown and described.

DESCRIPTION

FIG. 1 is a left-side elevational view of a food battering machine showing my new design;

FIG. 2 is a right-side elevational view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a second left-side elevational view thereof, showing the applicator end of the machine pivoted to an upward angle; and,

FIG. 8 is a third left-side elevational view thereof, showing the applicator end of the machine pivoted to a downward angle.
